GEORGE M. WILLIAMS, OF ELIZABETH, NEW JERSEY, ASSIGNOR TO P. LORILLARD COMPANY, INC., OF NEW YORK, N. Y., A CORPORATION OF NEW JERSEY.

UPSETTING-TOOL FOR EYELETS.

1,123,153.

Specification of Letters Patent. Patented Dec. 29, 1914.

Application filed June 16, 1914. Serial No. 845,357.

To all whom it may concern:

Be it known that I, GEORGE M. WILLIAMS, a citizen of the United States, residing at Elizabeth, in the county of Union and State 5 of New Jersey, have invented new and useful Improvements in Upsetting-Tools for Eyelets, of which the following is a specification.

This invention relates to a tool the purpose of which is to facilitate the upsetting 10 of eyelets, particularly when such eyelets are used for attaching together metal reinforcing bands, such as used on packing cases or boxes.

15 A principal object of the invention is to produce a tool for this purpose which can be readily applied between the box and superposed straps which are to be attached together, and which is adapted to upset the 20 eyelet when driven down through co-incident openings in the superposed straps.

25 A further object of the invention is to provide improved means for disengaging the attached parts or straps from each other after the eyelet has been upset. In the 30 present instance, the device includes an upwardly projecting stud which facilitates the upsetting of the eyelet, and the means for disengaging the device operates to disengage the eye from the stud referred to.

35 Further objects of the invention will appear more clearly hereinafter.

In the drawing, which fully illustrates the preferred embodiment of my invention, 40 Figure 1 is a plan of the tool showing a portion of a reinforcing strap the ends of which are to be connected by means of the tool. Fig. 2 is a longitudinal section through the tool, taken on the line 2—2 of Fig. 1, and showing a portion of a corner of the box, and also showing the superposed straps with the eyelet in position to be struck by a hammer to upset the eyelet. This view illustrates a hammer head about 45 to strike the eyelet. Fig. 3 is a view similar to Fig. 2, but showing only a portion of the tool and indicating the disengaging shoe in the act of disengaging attached straps from the eyelet upsetting means. Fig. 4 is a side 50 elevation with parts in section, showing the manner in which the eyelets connect the superposed ends of the reinforcing straps, and this view also shows the portion of the box to which the strap is attached. Fig. 5 55 is a perspective showing the end of a box

or packing case having the reinforcing metal strap, the ends of which are represented as attached together through the instrumentality of this tool. Fig. 6 is a side elevation showing a modified form of the 60 tool.

Referring more particularly to the parts, in its preferred form the tool comprises a base member or blade 10 which is in the form of an elongated plate, preferably having a forward beveled edge 11. On the side of this blade I provide means adapted to aline with co-incident openings 12 in the superposed strap ends, or straps 13 and 14. This upsetting means is preferably formed 70 of a small anvil 15 which may be of circular form and set in a socket 16 in the upper face of the blade. This anvil is preferably of circular form and preferably presents a stud 17 which projects upwardly from its 75 disk-shaped body, and at the base of this stud the anvil is preferably provided with a circumferential recess or groove 18. By reason of the beveled edge 11, this blade or face member 10 is readily inserted between 80 the wall 19 of the box 20 and the reinforcing strap, the ends of which are to be attached by an eye 21. In this way, the tool is inserted so that the stud 17 alines with 85 and projects upwardly into the alining opening, the eyelet 21 is then applied, as indicated in Fig. 2, with the lower end of its sleeve 22 resting in the groove 18, and the eyelet is then forced downwardly or driven 90 downwardly by means of a hammer 23, or other means.

If desired, in order to facilitate the upsetting of the lower end of the sleeve of the eyelet, I also provide the sleeve with a plurality of longitudinal cuts or incisions 24. 95 As the eyelet is forced downwardly, the groove 18 upsets or crimps outwardly the lower end of the sleeve so that it forms the lower end of said sleeve into a flange or clamped head 25, see Fig. 4, said head coming against the under face of the lower strap 14. After upsetting the eyelet in this way, the tool may be removed by slightly raising the straps and the eyelet until the stud is disengaged from the eyelet. The tool may 105 then be withdrawn.

110 Preferably, I provide means which may constitute an attachment for freeing the tool to permit its withdrawal, for this purpose, I prefer to provide a disengaging shoe 26

preferably in the form of a flat plate having pin and slot connections 27 with the blade, said pin and slot connections including the screw 28 lying in the slot 29 and retaining the shoe on the side of the blade. The forward end of this shoe is preferably formed into two forks 30 which preferably have forwardly beveled edges 31 adapted to slide under the attached straps and leave the same so as to disengage the eyelet from the stud. In order to guide the shoe 26 most effectively, I prefer to place the pins 27^a out of line with each other.

Any suitable means is provided for forcing the shoe under the straps. In Fig. 6 I illustrate a simple form of the invention, in which a disengaging shoe 32 is formed with an outwardly extending handle or finger 33 which may be grasped in the hand so as to shove the shoe in or out, or this finger 33 may be struck with a hammer a light blow and then similarly struck a light blow so as to drive it out again.

Again, in the preferred form of the tool, I provide means for enabling the disengaging shoe 26 to be moved in and out by actuating a handle 34 which is preferably pivotally attached at 35 on an extension 36 extending laterally from the blade. This handle 34 may be connected in any suitable manner such as by a link 37 with the rear end of the shoe, and if desired, a spring 38 may be provided at the pivot point 35, which tends to hold the spring in a withdrawn position, said spring preferably comprising a coil 39 wound around a pivot pin 35 and having an arm 40 pivoted in the extension 36, and a second arm 41 the end of which is thrust against the forward edge 42 of the handle or lever 34.

The blade 10 is preferably formed with an integral handle 43 opposite the handle 34. Evidently, by pressing the handle 34 toward the handle 43 the shoe will be forced forwardly on the plate, and when the pressure is released, the spring will return the shoe and handle to their normal position.

After the eyelet 21 has been upset, the strap ends or straps 13 and 14 may be secured to the box by suitable fastening devices such as nails 44, which may be driven in, as indicated in Fig. 4.

When the disengaging shoe is forced forwardly, evidently the forks 30 move past the eyelets 21 and on opposite sides of the same so as to operate effectively in disengaging the eye from the stud.

Although I have described the stud 17 as being formed on a separate piece or anvil 15, evidently, if desired, the blade could have its stud formed as an individual part thereof.

It is understood that the embodiment of the invention described above is only one of the many embodiments or forms the invention may take, and I do not wish to be lim-

ited in the practice of my invention, nor in my claims, to the particular embodiment set forth.

What I claim is:—

1. In a tool for attaching superposed parts having coincident openings, a relatively thin and flat base member adapted to be placed under the said parts, having means adapted to aline with and enter one of the said co-incident openings in said parts, said means having a form adapted to upset a fastening driven down through said openings to attach the parts, and means mounted on said base member for elevating the attached parts above the plane of the said alining means to permit the withdrawal of said base member. 75

2. In a tool for connecting superposed parts having coincident openings, a relatively thin and flat base member adapted to be placed under the said parts having means adapted to aline with and enter one of the said co-incident openings in said parts, said means having a form adapted to upset a fastening driven down through said 80 openings to connect the parts, means mounted on said base member for elevating the connected parts above the plane of the said alining means to permit the withdrawal of said base member therefrom after the fastening is upset, and a handle movably mounted on said tool and movably attached to said last named means for actuating the same. 90

3. In a tool for upsetting superposed parts having coincident openings, a relatively thin and flat base member adapted to be placed under the said parts having means adapted to aline with and enter one of the said coincident openings in said parts, said means having a form adapted to upset a fastening driven down through said openings to attach the parts, and means adjacent to said base member and movable relatively thereto for elevating the attached parts above the plane of the said alining means to permit the withdrawal of said base. 100

4. In a tool for connecting superposed metal straps having co-incident openings therethrough, in combination, a blade having a beveled edge adapted to be inserted under the superposed straps, an anvil on said blade having an upwardly projecting stud adapted to be received in the co-incident openings, said anvil having a form adapted to upset an eyelet driven down through said openings to connect said straps, and a tapered member mounted to move relatively to said blade to force the connected straps and eyelet off of said stud. 115

5. In a tool for connecting superposed straps having co-incident openings therethrough, in combination, a blade adapted to be forced under the straps, an anvil mount- 120

130

ed in said blade having an upwardly projecting stud adapted to be received in said openings, said stud being adapted to receive the sleeve of an eyelet when driven down through said openings, said anvil having an annular groove near the base of said stud, adapted to upset the sleeve of the eyelet against the face of the strap adjacent said blade, and a disengaging shoe guided on said blade and having a pair of tapered forks adapted to pass on opposite sides of said stud, for disengaging the attached straps from said stud.

6. In a tool for attaching superposed straps having co-incident openings, a blade having a beveled edge adapted to be forced under the superposed straps, a stud projecting upwardly from said blade adapted to receive the sleeve of an eyelet when driven downwardly through said openings, a disengaging shoe guided to move along said blade and having a beveled edge adapted to force its way between the straps to raise the straps and its upset eyelet from said stud, a spring tending to hold said shoe in a withdrawn position and a handle

connected with said shoe to actuate the same.

7. An upsetting tool for upsetting eyelets to connect the reinforcing metal straps on a box, having in combination, a blade adapted to be forced between the box and superposed straps, a stud on said blade for upsetting an eyelet driven through said straps, and a disengaging shoe mounted to slide on the guiding face of said blade and having a pin and slot connection with said blade to guide the same, said shoe having forks disposed near the longitudinal edges of said blade, said forks having beveled edges adapted to pass on opposite sides of a facing of the eyelet for raising the attached straps and disengaging the same from said stud.

In testimony whereof I have hereunto set my hand in presence of two subscribing witnesses.

GEORGE M. WILLIAMS.
